RAZOR

Henry Ostrovsky, Philadelphia, Pa.

Application January 27, 1945, Serial No. 574,850

15 Claims. (Cl. 30—58)

1

This invention relates to a razor and has particular reference to an improved safety razor construction involving novel means for holding replaceable blades, a construction which permits more effective and satisfactory holding of the razor when in operation, the provision for collapse of the razor into a compact structure when not in use, and the provision of means for holding a blade when not in use and for holding a blade and guiding it for proper stropping.

The foregoing will indicate the general objects of the present invention. These and other objects of the invention will become clear hereafter from the following description read in conjunction with the accompanying drawing, in which:

Figure 1 is an elevation illustrating the improved razor in its condition for use;

Figure 2 is a side elevation of the same illustrating in particular the method of holding it;

Figure 3 is a section taken on the plane indicated at 3—3 in Figure 1;

Figure 4 is a fragmentary side elevation similar to Figure 2 but showing the razor in collapsed position;

Figure 5 is a bottom end view of Figure 1 illustrating in particular the housing of a blade when not in use;

Figure 6 is a transverse section of the lower portion of the razor illustrating in particular the fashion in which a blade is held for stropping;

Figure 7 is a perspective view illustrating more clearly than in the previous figures the fashion in which the blade is held when in use;

Figure 8 is an enlarged sectional view similar to the upper portion of Figure 3 but showing in full lines the conditions existing when the blade is being either removed or placed in position for shaving and in dotted lines the position of the razor at the initiation of loading with a blade or the completion of removal of a blade;

Figure 9 is a perspective view showing an alternative construction involving a different stropping guide arrangement;

Figure 10 is a section taken on the plane indicated at 10—10 in Figure 9; and

Figure 11 is a sectional view similar to Figure 10 but illustrating a further modification.

Referring to Figures 1 to 8, inclusive, the razor shown therein comprises a main body portion 2 formed desirably of fairly light sheet metal and having a thin extension indicated at 4 which is turned upon itself at 6 to provide a portion 8 which is so sprung as to resiliently normally engage the portion 4. The upper end of the extension 8 is turned as indicated at 10 away from

2

the body and has its concave side desirably serrated or roughened as indicated at 12 to provide a good grip. Upturned ears 14 are desirably provided on opposite sides of extension 8, shaped as illustrated.

Pivoted at 16 to ears 18 of the body 2 is the head 20 of the razor which also may be formed of heavy sheet metal, shaped as indicated. This comprises a turned rear edge indicated at 22 to provide a socket for the back of the razor, an elongated transverse opening 24 and a series of teeth indicated at 26 projecting into the opening 24. As will be evident hereafter, a removable blade 28 will, when in operation, have its end portions resting upon projections 27 at the sides of the opening 24 and in engagement with the edge of the opening without engaging the teeth 26 and its rear edge in engagement with the turned portion 22.

20 The body 2 is provided with a resilient integral tongue 32 having a central pin-like extension 34 which, when the lever is in use for shaving, is adapted to project into a notch 38 forming an extension of an opening 36 in the head. Under 25 these conditions the pin 34 projects through an opening 40 in the blade, the blade being engaged by the shoulders 42 provided by the upper end of the tongue 32 on opposite sides of the pin 34.

Reference to Figures 1, 2, 3, 7 and 8 will indicate the handling of the blade and the fashion in which it is secured for shaving. If the head 20 is thrown to the position illustrated in dotted lines in Figure 8 the blade may be slipped through the opening 24, back edge first, so that its back edge 30 will rest on the turned portion 22 behind the body 2. If, now, by the action of the thumb, the tongue 32 is pressed rearwardly and the head 20 is swung clockwise, as viewed in Figure 8, the pin 34 will enter the opening 40 in the blade and by reason of its being pressed toward the left from its full line position illustrated in Figure 8 it will enter the notch 38. Ultimately, the position illustrated in Figure 3 is then secured. The back of the blade rests against the turned portion 22. The lower face of the blade rests against projections 27, but is clear of the teeth 26 projecting slightly beyond the same just sufficiently to secure proper shaving action and at the same time avoid cutting of the skin. The portions of the blade at the sides of the opening 40 then rest against the shoulders 42, while the pin 34 engages the back edge of the opening 40 and rests within the notch 38 exerting, as will be evident from Figures 3 and 8, a substantial clockwise force on the head 20 to keep it as far in a clock-

wise direction as is permitted by the rest of the construction. It may be noted that under these conditions the position of the blade is determined primarily by contact with the projections 27 and the opposite edge of the opening 24 whereby the blade is sprung between the projections 27 and the opposite edge of opening 24, rather than by some definite positioning surface associated with the turned portion 22. The result of the foregoing is to secure holding of the blade in accurately defined position for shaving.

As illustrated in Figure 5, the extensions 4 and 8 forming the handle of the razor are provided with lips 46 and 44, respectively, between which may be entered the blade which will be resiliently held by the spring action urging together the members 4 and 8. In order to provide a carrier for the blade when not in use an arm 48 is pivoted at 50 to the body 2 and has at its outer end an arrangement as illustrated, particularly in Figure 5, comprising portions 52 and 54 arranged to overlap the extensions 4 and 8 and lip 56 and 58 corresponding to lips 44 and 46 and provided to complete a proper hand grip. The holding of the razor is accomplished by gripping the widened assembly illustrated in Figure 5 by the fingers with the thumb resting in the saddle provided by the serrated face of the turned portion 18 of the extension 8 and the ears 14 which are shaped to provide a comfortable seat for the thumb, when the razor is held in one position, and as the lower portion of the ears 14 are also rounded the thumb may engage the lower faces of the ears 14. As the handle has considerable width when compared with its thickness, the handle can readily be grasped when the razor is inverted for shaving. By reason of this shaping of the elements of the handle, the razor is inevitably held by the same user in substantially the same definite position with resulting uniformity of shaving habits as contrasted with such razors as are provided with cylindrical or substantially cylindrical handles, as a result of which uniformity of shaving operations is essentially impossible.

The handle arrangement, as will be evident from Figure 5, provides a convenient housing for the blade when not in use. With the arm 48 turned about the pivot 50 to remove its end from the vicinity of the blade, the arrangement of the handle also provides a convenient mounting of the blade for stropping, as indicated in Figure 6. In this case, the blade is held resiliently by the clamping action between the members 4 and 8 and the ears 44 and 46 by resting on a strop indicated at S serve to position the blade edge at the proper angle for good stropping.

When it is desired to remove the blade from the razor it is only necessary to press upon the tongue 32 to release it from the notch 38 whereupon the head and the blade may be turned to the dotted line position illustrated in Figure 8. By holding the inside of the head downwardly and flicking the blade by a fingernail inserted in the opening 36, the cutting edge of the blade is caused to move forwardly through the opening 24 and when the rear edge clears the body 2 of the razor the blade will fall therefrom with its rear edge downward so that upon striking a support or falling into the palm of the hand, damage to the blade or cutting is avoided.

Figure 4 illustrates the position of the head of the razor when folded, it being evident that in the absence of a blade there is nothing to interfere with the turning of the head to the position

illustrated. Under such conditions and with the blade located as illustrated in Figure 5, a flat compact structure results so that the razor may be readily packed for transportation or put aside.

5 While the stropping arrangement of Figure 6 is highly satisfactory a more elaborate stropping arrangement may be provided as illustrated in Figures 9 and 10. In this case, 4' and 8' are the extensions of the handle portion of the razor 10 joined at the bend indicated at 6', the lips 44 and 46 being omitted. The blade 60 is entered between the extensions 4' and 8' and a stropping guide 62 is then secured to the handle by entrance of the end of the handle through an opening 66 in a turned portion 64 of the guide and clamping of the handle between a finger portion 68 and a resilient finger 70, the latter being desirably provided with a depression 72 forming a projection on its under side adapted to resiliently enter a slight depression in the member 4'. This assures definite positioning of the guide on the handle. A pair of rollers 74 and 76 are provided in the guide and are adapted to engage the strop S during the stropping operation as indicated in Figure 10. The strop may pass either between the members 64 or 68, or preferably one of them is cut away to clear the strop when it extends between the blade edge and either of the rollers 74 or 76, the other of these then being in position to act as a guide along the edge of the strop.

Figure 11 illustrates a modification in which the guide 62' is provided with guiding extensions 78 and 80 formed integral therewith in substitution for the rollers 74 and 76.

What I claim and desire to protect by Letters Patent is:

1. A safety razor having a handle, a head pivoted at its rear to opposite sides of the handle, 40 said head having a blade slot through the front thereof and a seat at the rear for the blade, and a leaf spring extending upwardly from the handle having a pin at its upper end adapted to enter an opening in a blade to spring the blade between the opposite edges of the opening and thereby retain the blade in shaving position.

2. A safety razor having a handle, a head pivoted at its rear to opposite sides of the handle, 50 said head having a blade slot through the front thereof and a seat at the rear for the blade, there being a notch in the head, and a leaf spring extending upwardly from the handle having a pin at its upper end adapted to enter an opening in a blade and to engage the notch in the head to spring the blade between the opposite edges of the opening and thereby position the blade in the head.

3. A safety razor having a handle, a head pivoted at its rear to opposite sides of the handle, 60 said head having a blade slot through the front thereof and a seat at the rear for the blade, there being a notch in the head, and a leaf spring extending upwardly from the handle having a shouldered pin at its upper end, the pin being adapted to enter an opening in a blade and the notch in the head, while the shoulders on the spring engage the face of the blade to spring the blade, whereby the blade is properly positioned in the head and the head is held in shaving position.

70 4. A safety razor having a head pivoted at its rear to opposite sides of the handle, said head having a blade slot through the front thereof, there being a notch and a seat in the head, a blade mounted in the head with its back in en-

gagement with the seat and the front thereof extending through the slot in the head, and a leaf spring having shoulders and a pin at its upper end, the pin extending through the opening in the blade and seated in the notch in the head, while the shoulders engage the face of the blade and tension the blade between the opposite faces of the slot.

5. A safety razor having a head pivoted at its rear to opposite sides of the handle, said head having a blade slot through the front thereof, the forward edge of the slot having teeth throughout its length, there being a notch and a seat in the head, a blade mounted in the head with its back in engagement with the seat and the front thereof extending through the slot in the head, and a leaf spring having shoulders and a pin at its upper end, the pin extending through the opening in the blade and seated in the notch in the head, while the shoulders engage the face of the blade and spring the blade between the rear edge of the slot and projections on the forward edge to tension the blade.

6. A safety razor having a head pivoted at its rear to the upper end of opposite sides of a handle formed of sheet metal, means for positioning a blade in the head including a spring seat, and a leaf spring formed of part of the handle, having means at its free end to engage an opening in the blade and the spring seat, to secure the blade in shaving position in the head and retain the head in a fixed position.

7. A safety razor having a head pivoted at its rear to opposite sides of a handle and adapted to be swung into a blade receiving position and into shaving position, means in the head for positioning a blade including a spring seat, and a leaf spring formed of part of the handle having means at its free end to engage an opening in the blade and the spring seat to secure the blade in shaving position in the head and retain the head in a fixed shaving position.

8. A safety razor having a head pivoted at its opposite sides to the upper end of a sheet metal handle and having a spring receiving opening, means in the head for positioning a blade in shaving position including a spring seat, said head being adapted to be shifted into blade receiving position, shaving position and collapsed position, and a leaf spring formed of part of the handle having means at its free end to engage the blade and spring seat to hold it in shaving position in the head when the head is moved to shaving position and to hold the head in fixed shaving position with relation to the handle when seated in the slot, the pivotal connections between the head and handle and the spring also being adapted to permit the head to be moved against the handle when the blade is removed, the free end of the spring extending through the opening in the head, whereby the head is retained in position against the handle by the engagement of the face of the spring against the slot in the head to hold the head in its collapsed position.

9. A handle for a safety razor formed of sheet metal, said handle having a broad body portion provided at its sides with lugs, a razor receiving head pivoted at its rear to said lugs, a leaf spring formed from the intermediate portion of the handle having means at its upper end for retaining a blade in the head and retaining the head in a fixed shaving position.

10. A handle for a safety razor formed of sheet metal, said handle having a broad body portion provided at its sides with lugs, a razor

receiving head pivoted at its rear to said lugs, a leaf spring formed from the intermediate portion of the handle having means at its upper end for retaining a blade in the head and retaining the head in fixed shaving position, the handle being of reduced width below the body and turned upon itself to provide a downwardly and an upwardly extending portion in contact with each other, an outwardly curved portion at the upper end of the upwardly extending portion,

5 and ears on the last mentioned portion below the curved portion having rounded faces, the curved upper portion of the spring and the concaved faces of the ears forming a saddle to seat the thumb.

10 11. A handle for a safety razor formed of sheet metal, said handle having a broad body portion provided at its sides with lugs, a razor receiving head pivoted at its rear to said lugs, a leaf spring formed from the intermediate portion of the handle having means at its upper end for retaining a blade in the head and retaining the head in a fixed shaving position, the handle being of reduced width below the body and turned upon itself to provide a downwardly and an upwardly extending portion in contact with each other, an outwardly curved portion at the upper end of the upwardly extending portion, ears

25 on the last mentioned portion below the curved portion having concaved faces, a lip extending laterally from each portion of the handle below the ears, an arm pivoted to the handle having portions adapted to overlap the handle portions in the plane of the lips on the handle and lips

30 on the overlapping portions of the lever, the lips on the handle and the lever forming a hand grip, when the lever portions overlap the handle portions.

35 12. A handle for a safety razor formed of sheet metal, said handle having a broad body portion provided at its sides with lugs, a razor receiving head pivoted to said lugs, the handle being of reduced width below the body and turned upon itself to provide a downwardly and an upwardly

40 extending portion in contact with each other, an outwardly curved portion at the upper end of the upwardly extending portion, ears on the last mentioned portion below the curved portion having concaved faces, forming a thumb engaging portion.

45 13. A handle for a safety razor formed of sheet metal, said handle having a broad body portion provided at its sides with lugs, a razor blade receiving head pivoted at its rear to said lugs and arranged to be folded against the handle, a leaf spring formed from the intermediate portion of the head having means at its upper end for retaining a blade in the head and retaining the head in a fixed shaving position and also to retain the head in its folded position, the handle being of reduced width below the body and turned upon itself to provide a downwardly and an upwardly extending portion in contact with each other, a lip extending laterally from

50 each portion of the handle below the ears, an arm pivoted to the handle having portions adapted to overlap the handle portions in the plane of the lips on the handle and lips on the overlapping portions of the lever, the lips on the handle and the lever forming a hand grip, when the lever portions overlap the handle portions, while the space between the handle portions in the plane of the lips form a carrier for the blade when not in use and when the overlapping portions of the lever are swung away from the handle, the lips

55 60 65 70 75

on the handle form positioning means for stropping a blade when in the carrier.

14. A folding safety razor having a blade carrier for the blade when not in use, comprising a handle formed of sheet metal having a wide body and narrow grasping portion extending downwardly therefrom, a head pivoted to the upper portion of the body, adapted to be swung against the body into collapsed position when not in use, the narrow portion of the handle extending downwardly and bent upon itself to form an upwardly extending member having a free upper end, the downwardly and upwardly extending members having lips extending laterally therefrom, a lever pivoted to the handle having portions adapted to overlap the downwardly and upwardly extending members of the handle in the plane of the lips on said members, lips on said lever members extending laterally therefrom in the opposite direction of the lips on the handle, the two sets of lips forming finger grasps on the handle, while the two members of the handle and the overlapping portions of the lever form a carrier for the blade when not in use.

15. A folding safety razor having a blade carrier for the blade when not in use, comprising a handle formed of sheet metal having a wide body and narrow grasping portion extending downwardly therefrom, a head pivoted to the upper portion of the body, adapted to be swung against

20

25

30

the body into collapsed position when not in use, the narrow portion of the handle extending downwardly and bent upon itself to form an upwardly extending member having a free upper end, the downwardly and upwardly extending members having lips extending laterally therefrom, a lever pivoted to the handle having portions adapted to overlap the downwardly and upwardly extending members of the handle in the plane of the lips on said members, lips on said lever members extending laterally therefrom in opposite direction of the lips on the handle, the two sets of lips forming finger grasps on the handle, while the two members of the handle and the overlapping portions of the lever form a carrier for the blade when not in use and a spring on the body portion for holding the head in collapsed position when not in use and for holding the blade and head in shaving position.
